UNITED STATES PATENT OFFICE.

MONTAGU BLATCHFORD, OF HALIFAX, ENGLAND, ASSIGNOR TO JOSEPH WILD & CO., OF NEW YORK CITY.

DESIGN FOR A CARPET-PATTERN.

Specification forming part of Design No. 5,705, dated March 26, 1872.

To all whom it may concern:

Be it known that I, MONTAGU BLATCHFORD, of Halifax, in the county of York, England, have invented an Improved Design for Carpet, of which the following is a specification:

The photographic illustration fully represents my new design.

This invention relates to several new forms of decorative figures, and in their combination with each other in application to carpets or other fabrics.

The first detail referred to is the design of a mixtilinear octagon, A, whose borders *a a* are continued beyond the angles to form projecting prongs, as of crossing branches. The center of this octagon is formed by a curvilinear quadrangle, *b*, from which tufts *d d* of foliage,

heart-shaped ornaments, &c., project toward the border, as shown. The second detail referred to is the design of the rosette B, having a smaller rosette, *e*, in the center and ornamental scroll-work *f* around the same, as described.

I claim as my invention—

1. The design of the mixtilinear octagon A, as shown.
2. The design of the rosette B, as shown.
3. The design for a carpet, consisting of the combination of the octagon A and rosette B, as shown and described.

MONTAGU BLATCHFORD.
